UNITED STATES PATENT OFFICE.

WILLARD E. CLOUGH, OF CONCORD, NEW HAMPSHIRE, ASSIGNOR OF ONE-HALF TO PHILIP PETHICK, OF SAME PLACE.

BORING-MACHINE.

SPECIFICATION forming part of Letters Patent No. 295,524, dated March 25, 1884.

Application filed October 29, 1383. (No model.)

To all whom it may concern:

Be it known that I, WILLARD E. CLOUGH, a citizen of the United States, residing at Concord, in the county of Merrimac and State of New Hampshire, have invented a certain new and useful Improvement in Boring-Machines; and I hereby declare that the following is a full and exact description thereof.

My improvements consist in providing a number of "bits," (say from two to twelve, more or less,) the "stocks" or "bit-spindles" for the same being mounted in bearings supported by arms projecting radially from a turret mounted and revolving upon a part of the frame of the improved borer, and in providing rolls upon the operating-table over which the timbers to be bored may be passed.

In the accompanying drawings, forming part of this specification, in which similar letters of reference indicate similar parts in all the figures, Figure 1 represents a front elevation of the improved borer as when in position ready for use. Fig. 2 is a side elevation of the same. Fig. 3 is a detailed plan view of the revolving turret carrying the bearings for six bit-spindles, showing a section of the frame upon which it is permitted to turn.

A is the line of the floor upon which the frame B B' of the boring-machine stands. The operating-table C slides up and down on said frame by means of ways D in the usual manner, the screw E and hand-wheel E' governing its motion in either direction.

F is the revolving turret, from which extend radially and equidistant from each other the arms f, upon the outer ends of which are suitable bearings, f', for the bit-spindles G.

g' represents spring-catches, one of which is provided for each bearing f', for the purpose of holding the turret F when ready to bore a piece of timber, and a slot, b, is formed in the front of the frame B' at the proper point to receive said catches g, as shown in the cross-sectional view Fig. 3.

H H are springs placed on the bit shafts or spindles G, which bear against and between friction or spur gears I and a casting, J, placed upon the top of said shafts G. A vertical shaft, K, hung in suitable bearings bolted to or cast upon the frame B', having upon its

lower end a friction or spur gear, L, which, when required, will engage with the friction or spur gears I, and upon its upper end the tight and loose pulleys, respectively M M', transmits the required motion and power to the bit-shafts G.

A lever, N, is fulcrumed to a projection from the back of the frame B' in such manner as that its forward end will be in position to bear upon any of the bit-spindles G when brought directly under the same, and by placing one's hand upon a handle, N', and applying pressure downward the bit Y which happens to be in the bit-spindle then in motion will be fed gradually into the work to be bored, and by removing one's hand from the lever N the spring H, by expansion, returns said bit-spindle and bit to the position shown in the drawings.

The object of providing so many bits upon the one machine is to facilitate the work to be accomplished by the borer when different-sized bits are constantly required, and avoid the necessity for changing the same by simply turning the turret and bringing the required size in front.

It is safe to say that with my improved borer three different-sized holes may be bored while a bit is being changed once in a machine constructed with but one bit-shaft. By providing rolls e in the operating-table C, its construction is rendered much more simple than would otherwise be possible, as by this means the customary rack and pinion used to adjust the table laterally are not required. Therefore the table C may be permanently bolted to the supporting-piece C', as is shown in the drawings, and but one motion is required—viz., up and down. Stay-rods O may be placed in suitable bearings formed upon a casting, 90 which is bolted to the front of the frame B, for use in holding the work down upon the table C, and a stand, P, bolted to the top of the table C, will carry the screw Q, which, by means of the hand-wheel R, will clamp said work between itself and the vertical back of the table C.

I am well aware that the idea of placing a number of bits in bearings arranged to revolve around a portion of the frame of a boring-

machine fitted for that purpose is as well adapted for use in a machine-shop, for which purpose it will be necessary to make a few changes in the construction of some other parts 5 of the machine—such, for instance, as providing cone-pulleys, instead of the pulleys M M', as also a different form of table would be required. I do not therefore confine my improvements to a boring-machine for wood-10 workers' use exclusively, but rather to boring-machines of all descriptions.

One advantage which I desire to state in a boring-machine constructed in the manner described is that while the shaft K may be continually in motion, all the bits may be quiet by placing the turret in such position as that neither of the catches *g* shall enter the slots *b*, and but one of the said bits can ever be set in motion at one time, for the reason that the 20 gear L can transmit power to but one of the gears I at the same time.

Having thus fully described my invention, I claim—

1. In a boring-machine constructed substantially as described, having a cored iron frame, B B', and an adjustable operating-table, C, a revolving turret, F, provided with arms *f*, containing bearings *f'* for the bit-spindles 25

G, operated by suitable gearing, in the manner and for the purpose specified.

2. In a boring-machine constructed substantially as described, having a cored iron frame formed of two or more parts, and an adjustable operating-table, C, the combination of two or more bit-spindles, G, and springs H, with the revolving turret F, operating as and for the purpose described and set forth.

3. In a boring-machine constructed substantially as described, the combination, with a cored iron frame, B B', of a vertical shaft, 40 K, carrying the pulleys M M', and a spur or friction gear, L, the spur or friction gear I, bit-spindles G, springs H, some suitable lever or levers, N, and the revolving turret F, all operating as described and set forth.

4. The combination, with the cored iron frame B B', having slot *b*, and a revolving turret, F, carrying the bit-spindles G, of suitable spring-catches, *g*, attached in some convenient manner to the arms *f*, and operating 50 within the said slot *b*, substantially as and for the purpose set forth.

WILLARD E. CLOUGH.
